REMOTE CONTROL FOR PITOT TUBES

Richard Star, Brooklyn, N. Y.

Application July 3, 1931. Serial No. 548,699

5 Claims. (Cl. 73—122)

This invention relates to controls for Pitot tubes and particularly to an improved remote control whereby a Pitot tube on a ship or boat may be raised and lowered from a distant point at any time, the object being to provide a simplified structure which may be readily installed and easily operated.

Another object of the invention is to provide a remote control for Pitot tubes whereby the same may be drawn in or forced outwardly through the action of means at a distant point, the structure being such that indicating means are provided at the distant control point to show when the Pitot tube has been moved inwardly for the desired distance or outwardly for the desired distance.

An additional object is to provide a remote control for Pitot tubes used in connection with gauges, the structure functioning to move the tube inwardly and outwardly without in any way disturbing the gauge.

In the accompanying drawing,

Figure 1 is a view in diagram showing part of a ship with a log and a remote control embodying the invention associated therewith for raising and lowering the Pitot tube.

Figure 2 is a perspective view with certain parts broken away illustrating the entire control device except for a section of pipe which connects the two principal parts.

Figure 3 is a longitudinal vertical sectional view through the indicating device shown in Figure 2.

Figure 4 is a sectional view on an enlarged scale of the controlling valves and associated parts embodying certain features of the invention.

Figure 5 is a perspective view of the indicating cup shown in Figure 3.

Referring to the accompanying drawing by numerals, 1 indicates a ship of any desired kind, said ship being provided with a log 2 for indicating the speed of the ship. Log 2 is provided with a structure 3 including a Pitot tube 4. The parts just described are old and well known and form no part of the present invention except in combination.

In installing the log 2, it must be installed near the lower part of the ship so that the tube 4 when in use may be continually submerged. This necessitates placing the device in out of the way places, even sometimes in the double bottom of the ship. When entering a drydock or many other places, it is desirable to raise the Pitot tube 4 and when this is necessary some one must go down into the lower part of the ship and raise this tube. This requires time and involves some

appreciable work so that in the past it has been found that quite often the captain will take a chance and leave the tube projecting which oftentimes results in breaking or bending of the tube, thus necessitating a new tube. This invention is intended to overcome these objections and provide an easily operated structure arranged in the chart room, pilot house or other desired point, which structure may be actuated at any time for withdrawing the Pitot tube or projecting the same outwardly into operative position.

As shown particularly in Figure 2, the Pitot tube is carried by a tubular structure 5 secured to the valve casing 6, which valve casing has bosses 7 and 8, boss 7 being adapted to receive bolts or screws for clamping the same firmly to the bottom of the ship or some other support. Boss 8 has the bars 9 bolted or otherwise clamped thereto, said bars being rigidly connected with clamps 10 and 11, which clamps surround and grip the respective cylinders 12 and 13. These clamps may be removably mounted in position, but are preferably held in position by suitable screws 14 and 15, so that the parts will be comparatively rigid. It will be understood that when the valve 16 is in the open position, the tube 4 may be moved inwardly and outwardly as desired, member 5 acting as a packing gland so that there will be no leakage. Members 5, 6 and 16 are old and well known and therefore form no part of the present invention except in combination with the other parts.

The cylinders 12 and 13 are of a length to permit a full withdrawal of the tube 4 and a full projection thereof below the bottom of the ship. These cylinders carry the respective pistons 17 and 18, which pistons are provided with reversibly positioned washers, that is, washers facing in opposite directions so as to contact with the cylinders as air or steam is supplied alternately at the respective ends for propelling the pistons and thereby pulling or pushing the tube 4. The piston rods 19 and 20 are connected to the respective pistons 17 and 18 and also to cross bar 21, which cross bar is provided with a tubular guide 22, said guide being rigidly connected not only to the cross bar 21, but with the Pitot tube 4 so that as the pistons move upwardly and downwardly, the rods 19 and 20 will move the cross bar 21 and Pitot tube 4 upwardly and downwardly. As shown in Figure 2, the Pitot tube is in its withdrawn or inner position while in Figure 1, the parts are in the downward or outer position. In order that these pistons shall function for moving the Pitot tube inward-

ly and outwardly air, steam or other fluid matter must be supplied to the respective cylinders at the respective ends. A pipe system 23 connects the lower ends of the cylinders 12 and 13 together while pipe system 24 connects the upper ends of the cylinders together so that the pistons in the respective cylinders will function simultaneously. A pipe 25 is connected to the pipe system 23 and a pipe 26 is connected with the pipe system 24. These pipes extend upwardly and also horizontally to a desired point as for instance the chart room 27 as illustrated in Figure 1. Both of these pipes are connected to the lower control valve 28 and also to the upper control valve 29. These control valves are shown more in detail in Figure 4, from which it will be seen that the respective valves are provided with the respective keys 30 and 31, said keys being of identical structure and provided with passageways 32 and 33 respectively. Valve 28 is connected through the pipe 34 to the hand pump 35 whereby hand pump 35 is operated and the principal parts are in the position shown in Figure 4. Air will pass through passageway 32 and into the pipe 26 and through this pipe into the upper ends of the cylinders 12 and 13 whereby the pistons will be forced downwardly and the Pitot tube will be forced to its outer position as shown in Figure 1. As the air flows in the path just set forth, and as the pistons 17 and 18 move downwardly, they will force air through the pipe system 23 through pipe 25 to valve 28, but as passageway 32 in this valve is out of registry, the air will continue up to the valve 29 and pass out passageway 33 to the pipe 36 and from thence into the indicator 37. Indicator 37 as shown in Figure 3 is provided with a glass tube 38' and a cap 39 having small passageway 40. An indicating cup 41 is loosely mounted in the tube 38' and is provided with one or more grooves 42 in the upper end whereby when the air passing through pipe 36 strikes the cup, it will raise the cup and usually cause the cup to press against cap 39; by reason of the grooves 42, the air will escape through passageway 40. As long as the cup 41 is held elevated, the person operating the device will realize that the pistons 17 and 18 are moving and consequently will continue to operate the pump 35. When the cup 41 drops downwardly to its lowest position as shown in Figure 3, the operator will know that the pistons have reached the end of their travel and consequently any further actuation of the pump 35 will be useless. After the Pitot tube has been forced outwardly as just described, it may be withdrawn by reverse action of the parts, namely, by drawing the handle 43 over to the position shown in Figure 2 which is the in position. At the same time the handle 44 is moved to the position shown in Figure 2. After the valves 28 and 29 have thus been set, pump 35 is actuated and air will then pass from pump 35 through passageway 32 into pipe 25 and downwardly through this pipe into the pipe system 23 and thence into the lower end of the cylinders 12 and 13. Air passing in this direction will raise the pistons and consequently will pull the tube 4 to its inner position. As the pistons move upwardly the air will be forced from the cylinders 12 and 13 through pipe 26 and this air will escape through the valve 29 into pipe 36 and thence into the glass tube 38' for raising cup 41. It will thus be seen that cup 41 is raised when the Pitot tube is being moved inwardly or is being moved outwardly.

The valves 28 and 29 and associated parts are positioned at any desired point on the ship any desired distance away from the Pitot tube but may be operated at any time for actuating the tube.

I claim:

1. A Pitot tube actuating structure including a pair of fixed cylinders, a piston arranged in each cylinder, a piston rod connected to each piston, said rod extending from said cylinders, means for connecting said rods to a Pitot tube, air pipes, one extending from one end of each cylinder to a distant point and the other extending from the other end of each cylinder to said distant point, a pair of valves connected to said pipes at a distant point for controlling the inlet and outlet of said pipes, and means for supplying air under pressure at said distant point, one of said valves being connected to said air supplying means for controlling the flow of air from said air supplying means to either of the pipes according to the direction of movement of said pistons.

2. The combination with a ship having a Pitot tube positioned to reciprocate inwardly and outwardly of the bottom of the ship, of an actuating structure for moving said Pitot tube inwardly and outwardly, said structure including a remote control, said structure comprising an air actuated power device, said device having a reciprocating member connected to said Pitot tube, a pair of air supply pipes connected to said power device and extending to a distant point, said pipes being adapted to supply air under pressure to the air actuated device to cause the same to function, control valves at said distant point interposed in said pipes, and means for supplying air under pressure to said pipes, one of said control valves being connected to said air supply means for controlling the flow of air from said air supply means to either of said pipes according to the position of said air actuated means for causing said Pitot tube to be moved inwardly or outwardly as desired.

3. A Pitot tube actuating structure including an air actuated power device directly connected with the Pitot tube, pipes leading from said power device to a distant point, means at said distant point for providing air under pressure to said pipes for actuating said power device, and a pair of control valves at said distant point controlling the flow of air in said pipes, one of said valves being connected to said air supply means for controlling the flow of air from said air supply means to either of the pipes according to the direction of movement of said power device, and the other valve controlling the exhaust of air from said pipes.

4. The combination with a vessel using a Pitot tube of means for moving said tube from an inoperative position to an operative position, said means including a pair of cylinders, a piston arranged in each cylinder, a piston rod connected with each piston, a crossbar connected to the outer end of each rod, means for connecting said crossbar to said Pitot tube, a pair of pipes for supplying air to said cylinders at the respective ends thereof, both of said pipes extending to a remote point, means at said remote point for supplying air under pressure to said pipes, a pair of control valves connected to said pipes at said distant point, one of said control valves being connected to said air supply means for controlling the flow of air from said air supply means to either of said pipes according to the direction of movement of said piston, and the other of said control

valves being connected to both of said pipes for regulating the exhaust from the respective pipes, and means actuated by the exhaust for indicating the movement of said tube.

5 5. A device for moving a Pitot tube from an operative position to an inoperative position and also in a reverse direction, comprising an air actuated power structure formed with a cylinder, a piston positioned to reciprocate in said cylinder, 10 a piston rod connected to and operated by said piston, means connecting said rod to said Pitot tube, air carrying pipes, one pipe being connected to each end of said cylinder and communicating with the interior of the cylinder, said pipes extending to a distant point, means at said distant point for supplying air under pressure to said pipes, a pair of valve mechanisms at said distant point, one of said mechanisms being connected to said air supply means for switching air from one pipe to the other and thereby supplying air to the respective ends of said cylinder at different times for actuating said piston and said piston rod for moving said tube from the operative position to an inoperative position and also in a reverse direction as desired, the other of said valve mechanisms actuating to control the exhaust from said pipes, and an air actuated indicator operated by the exhaust air connected with the last mentioned valve mechanism, said indicator being positioned to be actuated by the air from said last mentioned valve mechanism when the same is moved to the position for exhausting either of said pipes, thus indicating the movement and the position of said Pitot tube.
